Primary Examiner — Wendy L Arminio*Assistant Examiner* — Maheen Khurshid(57) **CLAIM**

The ornamental design for a swimming snorkel, as shown and described.

DESCRIPTION

FIG. 1 is a front, top perspective view of a swimming snorkel, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled 9 in FIG. 1; and,

FIG. 10 is an enlarged view of the area labeled 10 in FIG. 1.

The dashed lines in the figures illustrate portions of the swimming snorkel that form no part of the claimed design. The dot-dash-dot broken lines in FIGS. 1, 9 and 10 illustrate the boundaries of the enlarged views and form no part of the claimed design.
